BY Drake

ATTORNEY

UNITED STATES PATENT OFFICE.

WILLIAM ROEMER, OF NEWARK, NEW JERSEY.

BUCKLE.

SPECIFICATION forming part of Letters Patent No. 596,247, dated December 28, 1897.

Application filed March 22, 1897. Serial No. 628,600. (No model.)

To all whom it may concern:

Be it known that I, WILLIAM ROEMER, a citizen of the United States, residing at Newark, in the county of Essex and State of New Jersey, have invented certain new and useful Improvements in Belts and Buckles Therefor; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to provide a buckle of simple and light construction adapted to fasten a belt with greater firmness and security, and one adapted to catch or grasp the belt more quickly when tension is brought to bear thereon, and to secure other advantages and results, some of which may be referred to hereinafter in connection with the description of the working parts.

20 The invention is employed for fastening that class of belts in which perforations for the buckle-tongue are dispensed with, the buckle being adapted to engage the face of the belt and to clamp the same in position without injury to the finished surface of the belt.

25 The invention consists in the improved buckle and belt and in the arrangements and combinations of parts of the same, all substantially as will be hereinafter set forth, and 30 finally embraced in the clauses of the claim.

35 Referring to the accompanying drawings, in which like letters of reference indicate corresponding parts in each of the views, Figure 1 is a plan of the improved buckle. Fig. 40 2 is a plan of the under side or back of the same, and Fig. 3 is a central section at line α , Fig. 1. Fig. 4 is a side elevation showing the buckle in holding relation to the belt.

40 In said drawings, a indicates the belt, and b the buckle. Said buckle consists of an integral sheet-metal frame centrally open to receive the belt and allow of the holding tongue or lever working therein. The said frame comprises side bars b' and end bars b^2 , the said bars being longitudinally concavo-convex. The said bars are thus formed to secure the desired rigidity and strength with

the maximum lightness. The said bars are provided at their inner edges with inwardly-extending ears b^4 , which are perforated or otherwise formed to receive a pivotal pin or bar c , upon which the lever d is fulcrumed. The end bar b^2 at its inner edge has a short longitudinal tongue b^5 , which extends into the concavity of the said bar at its rear, forming a biting edge for the strap, which co-operates with the curved biting extremity of the holding-lever in fastening the strap, belt, or web a . The opposite end bar b^3 is also provided with a tongue b^6 at its inner rearward edge, which extends across, or nearly across, the concavity, forming a flat or somewhat rounded surface over which the belt, strap, or web may run with ease without damage thereto.

45 The holding tongue or lever d consists of an S-shaped piece of sheet metal viewed edge-wise, which is provided at its central portion with an integral eye d' for the fulcrumal pin or bar c , the said eye being preferably formed by pressing out the metal from the center of the tongue, as indicated, and turning it into the desired eye shape. The perforation d^2 thus formed serves as a receptacle for a hook e on the belt, web, or strap, by means of which said belt or strap is attached to the buckle. The said S-shaped tongue or lever has its turned edge d^2 adjacent to the biting-tongue b^5 so disposed as that it enters the concavity of the end bar just a little way from the said turned edge. When draft and tension are brought upon the belt and buckle, the belt will be forced into the said concavity over the said biting edge, pressing the belt therein and thus giving a firm hold of the buckle upon the said belt, by which the latter is fastened. Pressure upon the opposite end d^3 of the lever also tends to throw the biting edges into clamping or holding relation.

50 In operating the device I pass the belt first between the convex surfaces formed by the tongue b^6 of the bar b^3 and lever d . Thence I pass the belt over the outer face of said lever, entirely concealing the same from view, and pass it under the opposite end bar b^2 , where it is bent between the biting-surfaces of the said end bar and lever and is pressed by the said lever into the concavity of said

end bar. Having been adjusted to the waist of the wearer so as to fit the same properly, the said belt may be next fastened upon the body by hooking the belt at its free hooked 5 end *e* into the perforation or eye *d*², the hooking operation being both convenient and easy.

The construction thus described not only holds the belt with great firmness and precision, but presents a finished ornamental 10 surface to the sight and is inexpensive, durable, and light and is adapted for ladies' belts, garters, trusses, shawl-straps, and for use in any other line where belt-fasteners may be used, more particularly in connection with 15 personal wear.

Having thus described the invention, what I claim as new is—

1. The improved buckle herein described comprising a frame having end bars *b*², *b*³, 20 concave on the under side, one bar *b*², having at its inner edge a longitudinal extension which curves downward and outward until its edge lies in the concavity of said bar *b*², to form a biting edge, and the opposite bar *b*³, 25 having a similar tongue bent downward and outward to extend across the concavity of said bar *b*³, and an S-shaped lever fulcrumed to said frame, substantially as set forth.

2. The combination with the buckle-frame 30 *b*, having concavous end bars with under folded extensions *b*⁵, *b*⁶, and ears on the side

bars to support a transverse pin *c*, of an S-shaped lever fulcrumed on said pin *c*, and having a central perforation *d*², to allow the loose end of the belt, which is provided with 35 a suitable hook to be attached and detached at pleasure, substantially as set forth.

3. In a belt, the combination of the buckle-frame having concave end bars *b*², *b*³, extensions or tongues *b*⁵, *b*⁶, formed integrally on 40 the inner edges of said end bars and curving into the concavities of said end bars, side bars *b*', *b*', carrying at their middle points ears *b*⁴, *b*⁴, pin *c*, extending transversely across the frame the S-shaped lever *d* centrally pivoted on said pin *c*, and oppositely curved at its two free ends to engage the aforesaid extensions or tongues *b*⁵, *b*⁶, hook-perforation *d*², 45 in said lever, and a strap having the hook *e* at one end by which said end may be secured to the lever *d*, and the other end free to be passed over said lever *d*, and under the end bars of the buckle-frame, all said parts being arranged and combined, substantially as set forth.

In testimony that I claim the foregoing I have hereunto set my hand this 17th day of March, 1897.

WILLIAM ROEMER.
